UNITED STATES PATENT OFFICE.

DAMIAN HABIG, OF CUMBERLAND, MARYLAND.

STOVE.

SPECIFICATION forming part of Letters Patent No. 338,954, dated March 30, 1886.

Application filed May 12, 1885. Serial No. 165,927. (No model.)

To all whom it may concern:

Be it known that I, DAMIAN HABIG, a subject of the Emperor of Germany, and a resident of Cumberland, in the county of Allegany and State of Maryland, have invented 5 certain new and useful Improvements in Stoves; and I do hereby declare that the following is a full, clear, and exact description of the invention, which will enable others 10 skilled in the art to which it appertains to make and use the same, reference being had to the accompanying drawings, which form a part of this specification.

My invention relates to that class of stoves 15 commonly known as "heating-drums," which are adapted to heat a room or rooms above the one in which the stove is located; and it consists in the improved construction and combination of parts of a heating-drum of 20 the above-described class, which will be hereinafter fully described, and pointed out in the claim.

Referring to the annexed drawings, Figure 25 1 is a perspective view of my improved heating-drum, with portions of the outer casing broken away the better to illustrate the construction of the several parts; and Fig. 2 is a vertical sectional view taken on line $x-x$ in Fig. 1.

30 The same letters of reference indicate corresponding parts in both the figures.

Referring to the several parts by letter, A represents the body of the stove proper, upon 35 and in the open top of which fits the lower end of the heating-drum B, the said drum being of a less diameter than the top of the stove, and is inclosed by the outer casing, C, which is provided at a point near the bottom of the 40 said drum with a series of apertures, c , which serve to admit the air into the space between the heating-drum and the said outer casing.

A top plate, D, is placed upon the upper 45 end of the outer casing, and serves to support the hot-air pipe E, which conveys the heated air from the space between the heating-drum and the outer casing, C, to the room or rooms above, which it is desired to heat.

A metallic ring, F, which is supported upon the annular offset a on the outer casing, 50 C, serves to cover and conceal from view the row of apertures c , while a sufficient space is left between the said annular shield and the said apertures to admit of the free entrance of the air into the space between the outer casing and the heating-drum.

G G' G² represent three small smoke-pipes, which lead, respectively, from the side of the stove proper, the side of the heating-drum, and the top of the said drum, the opening 60 into each of these pipes being controlled by a valve or damper, g g' g², so that any one of the said smoke-pipes may be used, according to the location of the flue-hole in the chimney.

65 The heat, smoke, and flames from the body of the stove pass up into the heating-drum, and finally out through one of the before-mentioned smoke-pipes, the heat radiated from the heating-drum serving to heat the 70 air in the space surrounding the said drum, which then ascends up through the hot-air pipe E, to heat the room or rooms above, which it is desired to heat, the cold air from the exterior of the stove rushing in through 75 the series of apertures c to fill the vacuum thus created, and in turn becoming heated, to ascend through the hot-air pipe, thus creating a continual current of hot air up through the hot-air pipe.

80 From the foregoing description, taken in connection with the accompanying drawings, the construction and operation of my improved heating-drum will be readily understood without requiring further explanation.

85 It will be seen that my invention is very simple in construction, and at the same time exceedingly efficient in its operation.

Having thus described my invention, what I claim, and desire to secure by Letters Patent 90 of the United States, is—

In an attachment for stoves, the combination, with an outer casing having a series of perforations between two swaged beads, and a perforated cover provided with a hot-air 95 pipe leading therefrom, of a flaring shield fit-

ting said outer casing, covering the said perforations, an inwardly-extending lip provided said flange, upon, with an upwardly-extending flange secured to said outer casing below said series of perforations, and a bottomless heating-drum fitting upon said flange, substantially as and for the purpose set forth.

In testimony that I claim the foregoing as my own I have hereunto affixed my signature in presence of two witnesses.

DAMIAN HABIG.

Witnesses:

BRUCE HOBLITZELL,

F. M. OFFUTT.
